TABLE TENNIS NET ASSEMBLY

William V. Schnur, Glencoe, Ill., assignor to P. Becker & Company, Chicago, Ill., a corporation of Illinois

Application March 21, 1932. Serial No. 600,277

3 Claims. (Cl. 273-30)

My invention is directed to new and useful improvements in table tennis net assembly.

Table tennis may be briefly described as a game played on a table generally nine feet long and five feet wide, across the middle of which is stretched a net of given height supported at each end by standards clamped to the table. Wooden bats or racquets are used to hit celluloid balls over the net and return, and points are scored in favor of the adverse party whenever a player fails to hit the ball over the net and onto the other side of the table top.

The net to be used in this game is of a certain size and according to the rules, the top edge must be a given height from the table when in playing position. It is also desirable that the net can be speedily stretched to playing position and as readily dismantled. Heretofore the usual manner of securing the net in position has been by means of strings or tapes sewed to the ends of the net, the free ends of which are tied to the standards. This is unsatisfactory because the tapes fray and wear out easily, accurate adjustment of the net is difficult and the knots loosen, causing the net to sag.

The primary object of my invention is to provide attachments adapted to be secured to the ends of the net and cooperate with the standards, whereby the net is accurately and easily adjustable, is readily assembled and disassembled and is maintained in evenly stretched position.

Numerous other objects and advantages will be apparent from the following detailed description of the invention.

35 In the drawing:

Fig. 1 is an end elevation of a portion of a table (partly broken away) showing the net and standards installed thereon, utilizing the novel means of my invention for fastening the net to the standards.

Fig. 2 is a section along the line 2-2 in Fig. 1.

Fig. 3 is a section along line 3-3 in Fig. 2.

In detail 1 is a table top supported by legs 2. Standards 3 are clamped to the table top 1 by means of screws 4 having flat bearing surfaces 5 adapted to abut against the under side of the table top 1. The net is rectangular in shape and comprises a plurality of strings or cords 7a running horizontally and vertically and secured together at each intersection to form a netting of rectangular meshes and a border 7 formed by doubling any flexible material over the edges of the network and binding the said edges within said flexible material. T-shaped bolts 6 are flexibly connected with the net by means of leather pockets 8 which are fastened to the corners of the border 7 of the net by means of rivets 9 and which enclose and hold the heads 10 of the bolts 6, as clearly shown in Figs. 2 and 3.

60 The pockets 8 each comprise a substantially

rectangular shaped piece of leather or fabric or other flexible material, doubled over to form a pocket for the head 10 of the T-shaped bolt 6, the ends extending over each side of the border 7 and adjacent the corners of the netting and thus riveted together and to the border by means of a rivet 9. An opening 8a is provided in the doubled end of each pocket 8 to permit the threaded portion or stem of the bolt 6 to extend outwardly.

The standards 3 have holes 11 adapted to receive the stems of bolts 6 and the winged nuts 12 then thread onto the bolts 6 to support the net in substantially correct position. By tightening or loosening the nuts 12, the height and tension of the net can be accurately controlled. Between the rivets 9 and the heads 10 of the bolts 6, each pocket 8 is sewn together, as at 13, in order to keep the bolt in place and prevent its becoming lost out of the pocket when disassembled. Thus the bolt 6 is securely but flexibly attached to the pocket 8.

I claim:

1. A table tennis net assembly comprising a rectangular netting, a doubled border enclosing the edges of said netting, flexible pockets enclosing a portion of and clamped to said border adjacent each corner of said netting, bolts extending from and held against rotation by said pockets, a pair of standards having holes adapted to receive said bolts loosely and nuts adapted to be threaded on said bolts.

2. A table tennis net assembly comprising a rectangular netting, a border secured to the edges of said netting, pockets extending over each side of said border at each corner means extending through said pockets and said border for clamping said pockets to said border, headed bolts extending from and held thereby against rotation, a pair of standards having holes adapted to loosely receive said bolts and nuts adapted to be threaded on said bolts.

3. A table tennis net assembly comprising a rectangular netting, a border doubled to enclose the edges of said netting, the edges of said border being bound together, leather strips doubled to form pockets and enclosing said border, rivets extending through said pockets and said border adjacent each corner of said netting to clamp said pockets to said border, T headed bolts extending horizontally from said pockets the headed portions fitted within and held by said pockets against rotation, means for preventing the removal of said bolts from said pockets, a pair of standards having holes adapted to loosely receive said bolts and nuts adapted to be threaded on said bolts.

WILLIAM V. SCHNUR.
